US00D706036S

(12) **United States Design Patent**
Xi et al.

(10) **Patent No.:** **US D706,036 S**
(45) **Date of Patent:** **** Jun. 3, 2014**

(54) **ORAL CARE IMPLEMENT**

- (71) Applicant: **Colgate-Palmolive Company**, New York, NY (US)
- (72) Inventors: **Wen Jin Xi**, Shanghai (CN); **Yu Liu**, Jiangsu (CN); **Xiang Ji Ding**, Yangzhou (CN); **Yan Mei Ji**, Yangzhou (CN)
- (73) Assignee: **Colgate-Palmolive Company**, New York, NY (US)
- (**) Term: **14 Years**
- (21) Appl. No.: **29/444,030**
- (22) Filed: **Jan. 25, 2013**

Related U.S. Application Data

- (62) Division of application No. 29/358,641, filed on Mar. 30, 2010, now Pat. No. Des. 676,245.
- (51) **LOC (10) Cl.** **04-02**
(52) **U.S. Cl.**
USPC **D4/108**
- (58) **Field of Classification Search**

(57) **CLAIM**

The ornamental design for an oral care implement, as shown and described.

DESCRIPTION

FIG. 1 is a right, front perspective view of an oral care implement according to the new design;

FIG. 2 is a left, front perspective view thereof;

FIG. 3 is a right, rear perspective view thereof;

FIG. 4 is a left, rear perspective view thereof;

FIG. 5 is a front view thereof;

FIG. 6 is a rear view thereof;

FIG. 7 is a right side view thereof;

FIG. 8 is a left side view thereof;

FIG. 9 is an enlarged top view thereof; and,

FIG. 10 is an enlarged bottom view thereof.

The broken lines showing a handle illustrates a portion of the oral care implement that forms no part of the claimed design.

1 Claim, 5 Drawing Sheets
